US0D1002065S

(12) United States Design Patent (10) Patent No.: US D1,002,065 S
(45) Date of Patent: * Oct. 17, 2023

(54) SUSPENSION LIGHTING FIXTURE

(71) Applicant: Mahdi Thompson, Westfield, IN (US)

(72) Inventor: Mahdi Thompson, Westfield, IN (US)

() Term: 15 Years

(21) Appl. No.: 29/760,593

(22) Filed: Dec. 2, 2020

(51) LOC (14) Cl. 26-05

(52) U.S. Cl.

USPC D26/88

(58) Field of Classification Search

USPC D26/72, 80–92, 118, 120–124, 128, 130
